ABSTRACT

A manually actuatable check member for checkwisely holding a door in a desired open position wherein a said check is pivotably attached to a support so as to abuttingly engage a surface of the door, said support may be either a door frame, or, a link of a chain straddling an opened door and its frame, or, a rod of a shelf contained within a container closeable by its door.

DOOR AND A WINDOW CHECK

This application contains matter shown in abandoned case Ser. No. 472,398, filed July 6, 1965 and titles A DOOR AND A WINDOW CHECK, and also matter shown in abandoned case Ser. No. 311,067, filed Sept. 24, 1963, and titled CHECK OF OBJECTS MOVEMENT.

SUMMARY

In an article of manufacture, this invention relates to a new, novel and useful improvement in a door and window check, and to shown modifications thereof, each made for comprising an elongated or/and rectangular different shape, and any desirable size, and a resilient material, for example, a rubber, which can be self adhering, whenever desired, or a steel, or a plastic, according to a plan for using a said check. A said resilient material of a check resiliently indents under pressure from foreign objects without marring them.

For a purpose of pivotally and slideably attaching a said check with a first foreign object, for example, a screweye, or a rope or cord, or a rod, or a link of a chain, and a shelf within a container, and the like, a said check can be modified and comprise either:

an opening portion penetrating therethrough, and, whenever desirable, a slit portion leading into its said opening portion, or,

a rope-like portion tapering therefrom to its own free end portion while simultaneously decreasing in said resiliency thereof so that said free end portion of instant rope-like portion can be looped onto itself and made into a knot attachable with

a said first foreign object, whenever desired, or,

a groove portion for detachable attaching with a said first foreign object;

overall further described in detail hereinafter.

An object for making a said check is so that it can be pivotally or/and slidably attached with a said first foreign object which in turn can be supportably attached with a second foreign object, for example, either a frame of a door, or, a link of a chain straddling an opened door and its frame, or, a rod of a shelf contained within a container closeable by its door; overall for placing a said check nearby a closeably openable door for engaging a said check with a said opened door in a checking position for holding said door open; details of which follow.

When a door is open, an opening portion forms between it and its frame; at a top, and at a bottom of said door, and at opposite sides thereof; into which a said check can be removably inserted for checking said door open.

A check comprising a said elongated or rectangular shape comprises a larger length size compared with its width size, thereby a selection of a length and width size of a check can be made for engaging a closing opened door and its frame for sizing an opening portion between them.

In drawings forming a part of this application:

FIG. 1 shows a view of a check comprising an opening portion penetrating therethrough and through which a rope is penetrated and ends-wardly knotted for suitably maintaining attachments shown and described.

FIG. 2 is an enlarged view of said check and details of its attachment with a screweye originally shown in FIG. 1.

FIG. 3 shows a said check modified for comprising a ropelike portion tapering therefrom.

FIG. 4 shows a perspective view of a container having its shelf attached therein and its door checked by another modified check pivotally attached with a rod of said shelf.

10 FIG. 5 shows an enlarged perspective view of details related to FIG. 4 structure.

FIG. 6 shows an enlarged view of more details related to FIG. 4 structure.

FIG. 7 shows a plan view of another modified check 15 inserted into an opening portion between an open door and its frame which are straddled by a known door chain preventing said door from closing and limiting a size of its opening portion.

FIG. 8 shows a plan view of another modified check 20 attachable with a link of a chain, at least.

FIG. 9 shows a view of another modified check-link for uniteably linking with and between separated links of a chain as a link thereof.

DESCRIPTION

FIG. 1 shows a group of said checks, each comprising a check member 5, 6, and 7, each comprises elongation in its different shape and size, and each comprising an opening portion 4 penetrating therethrough, and each 30 is made from a said resilient material in a first form thereof, and in a second form thereof each can also comprise a self-adhering ability, too.

A rope or cord 3 first foreign object is slideably penetrated through each said opening portion 4 and through 35 an unseen closed eye portion 3 of a screweye 10 second foreign object, and a knot 8 and 11 formed and sized at opposite end portions of said rope or cord 3 for imprisoning them thereon, respectively.

An example of using each is shown by using check 40 member 5 shown placed width-wardly into an opening portion 12 formed between and by an opened door 2 third foreign object and its frame 1 fourth foreign object, for engaging them and checking said door 2 open. An opening portion 12 can be larger when a length-ward size of check member 5 is used instead, exemplified in FIG. 7.

Said door 2 is hingedly 16 attached with said frame 1, and when said door 2 is opened, an exemplified said opening portion 12 forms at a top and at a bottom and 50 at each of opposite sides of them into which a said check member can be engaged, FIG. 7 shows same happening at a side of said door 2 opposite to its hinged side. Thereby a check member can have any desirable shape and size. A said resilient material is preferred because a check member resiliently indents when pressurably engaged between a said door 2 and its frame 1 following a form of said door 2 for example, and is thereby firmly held between them. And when a check member material is self-adhering, it will releasably self-adhere in 55 its place between them also.

FIG. 2 shows an enlarged view of a check member 13 comprising opening portion 4 penetrating therethrough and penetrated by a said rope or cord 3 comprising knotted opposite end portions 14 and 15. Herein a said screweye 10 eye portion 9 is open for showing same, and instant rope 3 is slideably contained therein at 60 which time eye portion 9 can be closed, if desired, to

a size smaller than knot 15 for imprisoning check member 13 on said rope 3. Check member 13 opening portion 4 is smaller than knot 14 which can not reversibly penetrate therethrough, thereby check member 13 is imprisoned.

FIG. 3 shows a perspective view of a check member 5a preferably comprising a said resilient material and comprising an elongated rectangular shape, and a knotable portion 3a tapering therefrom to its free end portion smallest periphery thereof while simultaneously decreasing in resiliency while tapering so that at its said free end portion, it can be folded over onto itself and knotted. exemplified in said FIG. 1 at numeral 8, which can be attached with a screw eye 10 eye portion 9, in a manner in which said rope or cord 3 is attached in said FIG. 2, or with a link of a chain, as hereinafter said in FIG. 7.

FIG. 4 shows a view of an enclosure 33 forming an opening portion 27 therein, and having its opened door 28 moveably hinged 29 thereto and checked from closing shut by check member 32 pivotally positioned into its pathway.

With said enclosure 33 is a shelf 30a, and a shelf 30, each mounted by support means 31 along walls within said enclosure 33. Said shelf 30a can be any suitable type thereof. And said shelf 30 is made in a plan herein, and shows its rod 18 along a front border thereof and lengthwise entered through a said check member 32 of which its free long length end portion 25 pivotally abuts from said rod 18 and engages a surface of said door 28 and checks its closing shut movement and holds it open; an enlarged view of said check member 32 abutting from rod 18 as said, is shown in FIG. 6.

And now simultaneously and respectively viewing FIGS. 4, 5 and 6. Said check member 32 comprises an elongated teeter member comprising a flat top portion 41 and flat opposite side portions 42 and a bottom portion 43 comprising a fulcrum portion 22 thereof abutting downwardly therefrom and preferably comprising an arc-shaped outline with said flat opposite side portions 42 between a flat short length end portion 17 and a flat long length opposite end portion 25 thereof. Said fulcrum portion 22 thereof comprises an arcuately shaped opening portion 21 therethrough said sidewards.

Above described check member 32 is modified hereinafter to comprise shown groove portions 23 and 24.

FIG. 5 shows said shelf 30 comprises a bottom layer of rods 98, and a top layer of rods, laid together, and welded 20 together where they meet, to form a web-shaped said shelf 30. Said shelf 30 can comprise any number of said bottom rods and top rods, as desired. Said top layer of rods shows numerals lined to rod 18, rod 19, and rod 26 being used hereinafter.

Each of said bottom layer of rods 98 proceeds from a front to a back of said shelf 30 and is shaped along its length for covering a square or a rectangular shape thereof, each can be arcuately lengthwardly shaped too, when desired. And each of said top layer of rods proceeds from a side to opposite side of said shelf 30, and comprises an arcuate shape along its length.

When this shelf 30 is made, said rod 18 is inserted through opening portion 21 through said fulcrum portion 22 of said check member 32, and then rod 18 is welded 20 into its place along a front border of said shelf 30 with said check 32 located thereon and be-

tween two selected rods in the upper half portion of said bottom layer of rods 98, in effect overall forming a teeter frame thereat with a teetering said check member 32, firstly, so that check member 32 can be manually pivoted on rod 18, and, secondly, so that when said shelf 30 is mounted within enclosure 33, shelf 30 rod 18 with check member 32 pivotable thereon as said is located within said enclosure 33 with relation to said openably closeable door 28, that is, said check member 32 is manually pivoted on rod 18 for being held either in an unchecking position, or, in a door checking position, relative to said door 28.

FIG. 5 shows its said unchecking position in which said flat short length end portion 17 pivotally abuts from said rod 18 of shelf 30, and its said flat long length opposite end portion 25 lays on top of at least a rod of said top layer of rods of said shelf 30. Said planning of the location of shelf 30 in enclosure 33, positions it so that said flat short length end portion 17 in said short so that it does not enter into the pathway of closing door 28.

FIGS. 4 and 6 each shows said door checking position of said check member 32 in which its said flat long length opposite end portion 25 longwardly abuts from said rod 18 of shelf 30 for holding said door 28 open, as simultaneously said flat short length end portion 17 lays against at least a bottom of a rod of said top layer of rods of said shelf 30 for leverably checking said check member 32 in a firm position thereat while holding door 28 open.

Abovesaid check member 32 is modifiable to comprise in addition; that at a free end portion of said short length portion 17 of said bottom portion 43 thereof a groove portion 24 abuts downwardly therefrom, and, that at a free end portion of said long length portion 25 of said bottom portion 43 thereof a groove portion 23 abuts downwardly therefrom. Each said groove portion 24 and 23 comprises a groove formed thereinto between said flat opposite side portions 42 thereof, for a purpose of more firmly holding check member 32 with shelf 30 in each of its said unchecking position and door checking position. Said shelf 30 must be made in a plan for using with this modified check member 32 in that rod 19 and rod 26 of shelf 30 must be located therewith with relation to its rod 18, and also to the distance of each of said groove portions 24 and 23 of this modified check member 32 from its said fulcrum portion 22 pivotally attached with this rod 18, respectively, as shown. Noting, that in FIG. 5 groove portion 23 detachably more firmly holds with a top portion of rod 26, and also noting, that in FIGS. 4 and 6, groove portion 24 detachably more firmly holds with a bottom portion of rod 19.

As aforesaid, it is meant that a teeter frame with check member 32 as its teetering member is comprised and shown in the upper half portion of FIGS. 5 and 6; wherein the upper two bottom rods 98 are side and opposite side surfaces of said teeter frame, and suitable rods located in parallelism behind rod 18 can be selected for using as a back surface, and back rod thereof. Said groove portion 24 of said flat short length end portion 17 of said check 32, is stated as a means for detachably attaching said short length portion of said teetering member of said teeter frame with said back surface thereof.

FIG. 7 shows a check member 99 modified compared with said FIG. 3 check 5a in that a said ropelike portion

3a tapers from a central portion of its top portion 101 thereof. And FIG. 7 shows a fragment of an opened door 2, and a fragment of a frame 35 of said door 2, opening portion 34 is formed by and between them, and this check member 99 is inserted into said opening portion 34, using its length size, and brought into engagement with each of said opened door 2 and frame 35 for checking said door 2 open.

As said door 2 is checked open, simultaneously a door chain and lock means foreign object, is shown used for its purpose of straddling said opened door 2 and frame 35 at its said opening portion 34 for limiting a size of said opening portion 34. This check member 99 ropelike portion 3a is shown movably attached through and with an opening portion 46 formed through a clip means for forming an attachment foreign object which otherwise is removably clipped 47 onto and with a link 45 of said door chain, so that this check member 99 is suspended therefrom and is ready therewith for using; when this door chain and lock means is used as shown, and when it is inoperative too. Also, link 45a can have this ropelike portion 3a of check member 99 inserted through its opening portion and looped and knotted at resilient portions thereof, for a purpose of having said check member 99 suspending therefrom and in readiness for using, as shown.

A portion 37 of said door chain and lock means is attached 39 with said door 2, and another portion 38 thereof is attached 39 with said frame 35 and has a locking part 40 removably attached therewith, which is otherwise attached with an end link 45 of a series of links proceeding to a link 45 at an opposite end of this door chain, this opposite end link 45 is attached with said portion 37 of this door chain and lock means.

FIG. 8 shows a modified check member 60 comprising another size and shape and preferably said resilient material, and a bottom portion 100 comprising lengthwardly elongated four flat side portions, and lengthwardly elongated central portion 80, and a top portion 95 comprising a size selected in a plan for using same as hereinafter said. Said top portion 95 comprises an arcuate shape with flat opposite side portions 102 for defining an opening portion 81 therethrough. A first purpose for this article 60 relates to said FIG. 7 said door chain and lock means, of which said door chain thereof can be removably inserted through said opening portion 81 through said top portion 95 of this article 60, for pivotally and slideably suspending said article 60 from said door chain so that at least when said door chain limits a size of opening portion 34 formed by and between door 2 and frame 35 simultaneously said article 60 said bottom portion 100 can be removably inserted into said opening portion 34 for engaging said door 2 and frame 35 and holding door 2 open. An example of said door chain inserted through opening portion 81 is shown in FIG. 5 where said rod 18 is inserted into said opening portion 21 through said fulcrum portion 22 of check member 32.

Continuing with this FIG. 8, check member 60 said top portion 95 can comprise a slit portion 82 therethrough and leading into said opening portion 81 thereof, for a second purpose, that said resilient material at said slit portion 82 of said top portion 95 can be manually resiliently expanded for inserting through said slit portion 82 a link 45a of said door chain in FIG. 7, for pivotally and slidably attaching them together so that said bottom portion 100 of this article 60 is ready

for using for holding door 2 open in a manner herein before said.

FIG. 9 shows a modified check member 83 called a check-link herein, comprising preferably a metal material, for example, a metal used in making a link of a door chain as shown in FIG. 7. This article 83 comprises a top-link portion 45b, a central portion 83a, and a bottom portion 90 thereof. Said top-link portion 45b comprises a hereinafter described size, and an arcuate rodlike shape defining an opening portion 45c therethrough, and a bottom central portion 45d integral with said control portion 83a thereof. Said central portion 83a thereof comprises necklike lengthward elongation and is bottomwardly integral with a top-central portion comprised by said bottom portion 90 thereof. Said bottom portion 90 thereof also comprises a horizontal flat rectangular shape, but also can be square shaped, or any desirable shape. Said hereinafter described size of said top-link portion 45b, and a said shape thereof, preferably relate to same of a link of a door chain and lock means as shown in said FIG. 7, for a purpose that said top-link portion 45b thereof pivotally and slideably links with and between a selected separated pair of links 45 of said door chain, preferably becoming positioned like link 45a located at an opening portion 34 between door 2 and frame 35, shown in FIG. 7, thereby this article 83 can become a link part of a said door chain so that said central portion 83a and bottom portion 90 thereof suspend in readiness therefrom nearby opening portion 34, for engaging said bottom portion 90 thereof with door 2 and frame 35 for holding door 2 open.

I claim:

1. In an article of manufacture, a teeter member for attaching with a shelf, said article made in a plan and comprising a resilient material, and said article comprises elongation, and a size at least lengthwisely approximate to an adult's grasping hand, without restriction thereto, said teeter member comprises a flat top portion thereof and flat opposite side portions, and a bottom portion thereof comprising a fulcrum portion thereof abutting downwardly therefrom preferably comprising an arc-shaped outline with said flat opposite side portions located between a flat short length end portion and a flat long length opposite end portion of instant bottom portion thereof, said fulcrum portion thereof comprises a circularly shaped opening portion therethrough said sidewise, purposive so that said circularly shaped opening portion through said fulcrum portion thereof fits in a pivotable relation with and along a first foreign object, for example, a portion of an insertable border rod of rods of a shelf when said shelf is made, thereby in a first position of said article therewith simultaneously said flat short length end portion extends freely a said short length distance from said shelf and said flat long length opposite end portion thereof lays on top of said shelf, when a finger pivots said article so that said flat short length end portion thereof contacts against a bottom of an interiorly located said first foreign object of said shelf in a held firm second position as simultaneously said flat long length opposite end portion thereof extends a said long length distance from said shelf in said held firm position, a finger reversibly pivots said article to said first position thereof.
2. In an article of manufacture, as defined in claim 1, and adding thereto, in combination with, said article

said bottom portion said flat short length end portion comprises a groove portion abutting downwardly therefrom at its free end border, said groove portion said sidewise centrally grooved, purposive so that instant groove portion grooveably fits and holds in a said held firmer position with a bottom of a said first foreign object interiorly located in said shelf.

3. In an article of manufacture, as defined in claim 1 and adding thereto, in combination with, and in a working relation with, a said rod at a border of a shelf, said 10 rod comprises a length portion between an end portion and an opposite end portion thereof, said length portion comprises a circularly shape said planned in size relative to a size of said circularly shaped opening portion penetrating through said fulcrum portion of said 15 teeter member, purposive so that instant rod said lengthwise inserts into said opening portion through said fulcrum portion of said teeter member which thereby fits on a portion thereof in said pivotal relation.

4. In an article of manufacture, a teeter-frame comprising a teetering member thereof, in a plan, said teeter-frame comprises in overall spaced apart relationship, a side surface, opposite side surface and a back surface thereof, and a front rod thereof comprising a straight length and a circularly shaped periphery, in combination with, said teetering member thereof comprises an elongated length comprising at least a bottom portion comprising a fulcrum portion thereof downwardly between, and simultaneously for designating, a 20 short length portion and a long length portion of instant said teetering member thereof,

said fulcrum portion thereof comprises an opening portion penetrating sidewardly therethrough relative to said elongated length of instant teetering member thereof, said opening portion comprises a circularly shape sized pivotally relative to said circularly shape of said front rod thereof, purposive so that when said article is made, said teetering member thereof said fulcrum portion said opening portion fits in a pivotal and oppositely pivotable relation on a portion of said front rod thereof in an idle first position of said article overall in which a mid-point of said long length portion of said teetering member thereof lays on top of a portion of said back surface of said teeter-frame and said short length portion of said teetering member thereof overall extends freely in front of said front rod thereof and is pivoted therebeneath to become portionally and lever-wisely pressed upwardly against a bottom of said back surface of said teeter-frame by a weight of said long length portion of said teetering member thereof extending freely in front of said front rod thereof in a work second position of said article, said teetering member thereof oppositely pivotable to said idle first position of said article.

5. In an article of manufacture, as defined in claim 4, and adding thereto, means for detachably attaching 60 said short length portion of said teetering member thereof with said back surface of said teeter-frame.

6. In an article of manufacture, a teeter-frame comprising a teetering member thereof, in a plan, said teeter-frame comprises a pair of side surfaces spaced apart, and a front rod, a middle rod, and a back rod thereof overall aligned in unequal spaced apart relationship to each other and endwisely attached with one of said pair

5 of said surfaces and opposite endwisely attached with the other one of said pair of side surfaces, in combination with,

a said teetering member thereof comprises an elongated length comprising at least a bottom surface comprising a fulcrum portion thereof abutting downwardly between, and simultaneously for designating, a short length portion and a long length portion of instant said teetering member thereof, said fulcrum portion thereof comprises an opening portion thereof therethrough sidewise relative to said elongated length of instant said teetering member thereof, purposive so that when said article is made, said front rod thereof penetrates into said opening portion through said fulcrum portion thereof for pivotally securing said teetering member thereof on a portion of instant said front rod thereof in a work first position of said article, in which said long length portion of said teetering member extends and suspends in front of said article and weightwisely leverably firmly engages its said short portion against a bottom of said middle rod thereof, and also so that said teetering member thereof pivots wheresaid into an idle second position of said article in which its said long length portion lays at least on top of said back rod thereof as its said short length portion suspends and extends in front of said article, said teetering member thereof oppositely pivots to said work first position of said article by using a finger for doing this.

7. In an article of manufacture, a door-check, said article comprises a resilient material, and a size and a weight readily handleable for porting said article, and said article comprises a bottom end portion, a central portion, and a top portion thereof, said bottom end portion thereof comprises four flat side portions, said central portion thereof tapers inwardly and upwardly in elongation relative to said bottom end portion thereof, said top portion thereof comprises an arcuate shape with flat opposite side portions with an opening portion forming said sidewardly therethrough, for a purpose that said article is handleable overall for removably engaging two opposite side portions of said four flat side portions of said bottom end portion thereof in a said resilient relationship with and between an aligned portion of each of a first foreign object and a second foreign object, for examples, a closeably opened door, and its frame, respectively, for said checking said second foreign object closeably opened as said and, for removably inserting a third foreign object, for example, a chain of a chain and a lock set, in respective association with each of said first and second foreign objects, through said first opening portion of said top portion thereof, for readying said article therewith for using as above-said.

8. In an article of manufacture, a door-checklink for linking with a link of a chain, said door-checklink comprises a said link top portion, a central portion and a bottom portion thereof, said link top portion thereof rodlike surrounds an opening therethrough and comprises at least an arcuate shape selectable in its size relative to a size and a shape of a hereinafter said first foreign object, said central portion thereof relatively elongating necklike, said bottom portion thereof elongating bodylike relative to said central portion thereof and comprises at least four flat side portions, for a first purpose that said link top portion thereof said opening

wisely links with, and is carriably hung from, a said first foreign object for example, a desirably positioned link of a door-chain and lock set suitably attached with each of a second foreign object, a closeably opened door, and a third foreign object, a frame of said second foreign object, said article disposed in readiness thereat for a second purpose for handling for engaging at least two opposite side portions of said four flat side portions of said bottom portion thereof simultaneously with and

between an aligned portion of each of said second and third foreign objects, for said checking said second foreign object closeably opened as said.

5 9. In an article of manufacture, as defined in said claim 8, and adding thereto, in combination with, as an element in this claim, means for said linking with said link top portion of said door-check link.
